(57) **CLAIM**

The ornamental design for a head-up display for vehicle, as
shown and described.

DESCRIPTION

FIG. 1 is a front perspective view of a head-up display for
vehicle showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines showing on the drawing disclosure are for
illustrative purposes only and form no part of the claimed
design.
